Ms. 381

W G Hallman, of Philadelphia Penn
Letters Patent No 381 Dated June 10th 1851

The Schedule referred to in these letters patent, and making part of the same

Description of Design of Frame and Door for Stone front and ranges &c

The frame (a) consists of a molding (b) around an opening of nearly an oblong square form, the upper part being slightly rounded at the corners and rising up from the sides to the centre at a very low angle like a pointed arch; the outer border of this frame is composed of the elementary foliage (c) and scroll work extending from the lower corners up the sides and over the top, where it is more enriched, the centre or key at top terminating in a shell (d). The bottom has a litter scroll (e); the inside border of this frame is a plain beading. The door (f) is divided on either half is a die, or panel the outline of which is formed by ~~scrolls~~ terminating at the corners with a bevel within this at the centre is a rosette above and below which are foliated scroll work supporters, but one door and a portion of the ornaments when they are duplicate and shown in the drawing

Having thus fully described my design what I claim therein and desire to have secured by Letters Patent is the design or ornamental pattern herein fully set forth and delineated
